(57) **CLAIM**

The ornamental design for a side hardbag for a motorcycle, as shown and described.

DESCRIPTION

FIG. 1, is a perspective view of a left side hardbag for a motorcycle according to the invention;

FIG. 2, is a side view thereof;

FIG. 3, is a reverse side view thereof;

FIG. 4, is a top view thereof;

FIG. 5, is a bottom view thereof;

FIG. 6 is a front view thereof;

FIG. 7 is a back view thereof; and

FIG. 8 is an isometric view of the side hardbag for a motorcycle as it would appear in an exemplary environment.

FIG. 9 is a perspective view of a right side hardbag for a motorcycle according to the invention;

FIG. 10 is a side view thereof;

FIG. 11 is a reverse side view thereof;

FIG. 12 is a top view thereof;

FIG. 13 is a bottom view thereof;

FIG. 14 is a front view thereof; and,

FIG. 15 is a back view thereof.

The broken lines shown in the drawings represent portions of the invention that form no part of the claimed design.

1 Claim, 11 Drawing Sheets
